FUEL-FEEDING DEVICE

Michael E. Bafaro, Cicero, Ill.

Application July 26, 1937, Serial No. 155,601

4 Claims. (Cl. 103—38)

The invention relates to fuel feeding devices for internal combustion engines and for purposes of illustration is shown as employed with a rotary internal combustion engine of the type 5 wherein air is compressed and delivered into the combustion chambers at temperatures above the ignition point of the fuel, and the use of spark plugs or other ignition devices is unnecessary. A full description and disclosure of the engine is given in order that the operation of the device 10 as connected therewith may be better understood.

An object of the invention is the provision of improved means for injecting fuel and air into 15 the combustion chambers of an engine whereby the fuel is highly atomized and perfectly disseminated through the air charge to form a turbulent combustible mixture resulting in even and complete burning during the explosion, and prevents combustion lag and inefficient throttling 20 such as is frequently incidental to existing compression ignition motors.

Another object of the invention is the provision of an improved fuel injection pump which is 25 simple in construction since it requires no needle valves, springs, or check valves, and utilizes the Venturi principle at its nozzle for reducing the pressure required to inject fuel into the compressed air charges as they pass from the compression chambers into the combustion chambers. 30

Other objects of the invention include the provision of improvements tending to simplicity, durability, efficiency, and low combustion cost.

Many other objects and advantages of the 35 construction herein shown and described will be obvious to those skilled in the art from the disclosure herein given.

To this end my invention consists in the novel construction, arrangement, and combination of 40 parts herein shown and described, and more particularly pointed out in the appended claims.

Referring now to the drawings wherein like 45 reference characters indicate like or corresponding parts:

Fig. 1 is a longitudinal vertical section of the 50 engine, taken along line 1—1 of Fig. 2;

Fig. 2 is a horizontal section, taken along the line 2—2 of Fig. 1;

Fig. 3 is a transverse vertical section taken 55 along the line 3—3 of Fig. 1;

Fig. 4 is a transverse vertical section, taken 60 along the line 4—4 of Fig. 1;

Fig. 5 is a sectional view taken along the line 5—5 of Fig. 4;

Fig. 6 is a sectional view taken along the line 6—6 of Fig. 7 illustrating the construction of by-pass valves, throttle control mechanism and other details;

Fig. 7 is a transverse sectional view, taken along 65 the line 7—7 of Fig. 1;

Fig. 8 is a transverse sectional view taken along the line 8—8 of Fig. 1; and

Fig. 9 is a view taken along the line 9—9 of Fig. 2.

Referring now more particularly to the drawings, the numeral 10 generally designates an oblong casing or housing, one end of which provides a pair of combustion chambers 11a and 11b and the other end provides a pair of combustion chambers numbered 12a and 12b, respectively. 10 Extending longitudinally of the housing 10 is a shaft 13 having a cylindrical shaped rotor 14, positioned in and separating the chambers 11a and 11b. The other end of the shaft 13 is axially aligned with and suitably connected with a rotor 15, similar to the rotor 14, positioned in and separating the chambers 12a and 12b. The rotor 15 is formed on the end of a power shaft 16 projecting from the casing 10 in axial alignment with the shaft 13. The outer ends of the rotors 14 and 15 are each supported by a plurality of conical bearings 17. The bearings 17 for the rotor 14 are positioned between an outer race 18 and an inner race 19, adjacent a plate 20 suitably fastened to the casing 10 by bolts 21. 25 A plate 22, fastened to the casing 10 by bolts 23, encloses an inner race 24 and an outer race 25 for the bearings 17 supporting the outer end of the rotor 15. The two sets of bearings 17 and their respective cooperating races are so arranged 30 as to carry the combined radial and thrust loads, to which the rotors 14 and 15 and the shafts 13 and 16 are subjected, with a minimum of frictional resistance to the operation of the rotors and shafts. 35

The rotors 14 and 15 each carry a pair of pistons 26 radially movable in and slideably fitting a diametric bore 27 extending through the rotors. Each bore 27 contains a compression spring 28 having its ends extending into recesses 28a provided by the adjacent ends of the pistons 26. The length of each piston 26 is substantially equal to the radius of the rotor in which it is mounted, and the lengths of the springs 28 are such that they permit complete retraction of 45 the pistons in passing from one combustion chamber to the other. The resilience of the springs 28 constantly tends to move the pistons outwardly, the pressure of the springs on the pistons being supplemented by centrifugal force to 50 maintain the pistons in close fitting contact with the peripheral bounding walls of the combustion chambers during rotation thereof. The longitudinal axes of the pistons 26 mounted on the rotor 14 are positioned parallel to and extend at 55 right angles to the longitudinal axes of the pistons mounted on the rotor 15. The chambers 11a, 11b, 12a, and 12b are preferably of the same size and the curvature, configuration and relative positions of the peripheral bounding walls of the 60

combustion chambers 11a and 11b are identical with those shown in Fig. 3 for the chambers 12a and 12b, respectively. The curved peripheral walls of the chambers 11a and 11b and of the chambers 12a and 12b are so spaced relative to the longitudinal axis of the rotor positioned therein that the pistons 26 comprising a pair are simultaneously moved outwardly and inwardly in equal amounts as the rotor turns.

10 Air under pressure is admitted to the combustion chambers 11a, 11b, 12a, and 12b at predetermined time intervals in a manner herein-after more particularly described. The air is compressed by two pairs of compression pistons 29 operatively connected with the shaft 13, the pistons being respectively reciprocally movable in compression chambers 30a, 30b, 30c, and 30d, positioned alongside and in relatively close proximity to the combustion chambers. The pistons 29 comprising each pair are rigidly connected by rods 31 so that they move together and at the same rate in the compression chambers. The rods 31 each terminate in a generally U-shaped member 32 fastened to the adjacent member by bolts 33. The space 34 between the connected members 32 provides a runway for a pair of blocks 35 forming a journalled bearing for the eccentric of a crank shaft 36. The inner ends of the crank shafts 36 each carry a bevelled pinion 37 in meshing engagement with a bevelled gear 38 mounted on the shaft 13. The crank shafts 36 are supported at their outer ends by a plurality of conical bearings 39, each set of bearings being positioned between an outer race 40 and an inner race 41 adjacent a cover plate 42 which is fastened to the casing 10 by bolts 43. The bearings 39 are adapted to carry both radial and thrust forces from the crank shafts 36.

40 The bevelled pinions 37 and each shaft 36 make two complete revolutions in opposite directions for each revolution of the shaft 13 and the rotors 14 and 15. Each revolution of the crank shafts 36, by reason of their eccentric connections with the rods 31, moves the pistons 29 from one end of the compression chambers to the other and then back to the opposite end of the chambers, thereby producing a complete compression and suction stroke of all four pistons 29. Both pairs of pistons 29 are moved simultaneously in the same direction by meshing the pinions 37 with the gear 38 so that the crank of one shaft 36 is diametrically opposite the crank of the other shaft when the pistons are at the mid-point of their travel. During the compression stroke of one piston 29 of each pair, the other piston 29 of each pair is making a suction stroke and vice versa. In Fig. 2, one piston 29 of each pair is shown as at the end of its compression stroke and the other piston of each pair as at the end of its suction stroke. The compression chambers are each connected with the atmosphere by a conduit 44 which is closed by a poppet valve 45. During the suction strokes of the pistons 29, the valves 45 controlling the corresponding compression chambers open for admission of air, the valves otherwise remaining closed.

70 The conduits 46a, 46b, 46c, and 46d, respectively connect the compression ends of the chambers 30a, 30b, 30c, and 30d with the combustion chambers 11b, 11a, 12b, and 12a. Rotary by-pass valves 47a, 47b, 47c, and 47d, respectively closing the conduits 46a, 46b, 46c, and 46d during the suction strokes of the corresponding pistons 29 and preferably remain closed until the compression strokes are completed to a point wherein the

5 air in the compression chambers is highly compressed and preferably from one-seventeenth to one-eighteenth of its normal volume. When the air has reached its maximum compression as described, the by-pass valves open to admit the compressed air into the combustion chambers, the valves opening and air being admitted while the pistons 26 are passing over the exit ends of the conduits leading to the combustion chambers, the valves closing when the pistons have travelled 10 through an arc of approximately ten degrees in the combustion chambers. The compression of the air raises its temperature above the ignition point of the fuel and by reason of the proximity of the compression chambers to the combustion 15 chambers, the conduits 46a, 46b, 46c and 46d are relatively short and the loss of heat by the air in travelling through the conduits is negligible.

The by-pass valves are slightly tapered at their inner ends and closely fit the constricted portion 20 of bores 65 in which they are respectively mounted. A spring 66 positioned in the upper end of each bore 65 holds the by-pass valves seated to a close fit within the bores and thereby prevents escape of air around the valves. 25

The by-pass valves 46a and 46b are simultaneously rotated in the same direction by the oscillation of two arms 48 each having an arcuate toothed end respectively meshing with gears 49, mounted or formed on the upper ends of the 30 valves. The arms 48 are each pivotally mounted on a pin 50 positioned intermediate their ends. A link 51 is pivotally connected with the lower ends of the arms 48 by bolts 49a, the link being reciprocally movable to oscillate the arms by the 35 rotation of a pair of cams 52 oppositely positioned on the shaft 13. A downwardly projecting member 53, integrally formed with the link 51, provides a cam face 54 which is successively engaged by the cams 52. Each resulting cam 40 movement of the link 51 moves the toothed ends of the arms 48 to the right as observed in Fig. 6, and thereby simultaneously oscillates the valves 47a and 47b through ninety degrees in the same direction twice for each complete revolution of 45 the shaft 13. Oscillation of the valves 47a and 47b through ninety degrees as described, opens the valves by bringing a transverse bore 60 extending through the lower ends of each valve, into register with the conduits 46a and 46b respectively. A plunger 55, reciprocally movable in a bore 56, is maintained in contact with the link 51 by a compression spring 57. The spring 57 yields to permit the described cam movement of the member 53 and the link 51 and upon disengagement of the members and the cams 52, immediately returns the link to the position shown, thereby returning the valves 47a and 47b to their respective closed positions. 55

The valves 47c and 47d are oscillated, in the same manner as the valves 47a and 47b are oscillated, to open and close the air conduits 46c and 46d. For this purpose, I provide another pair of arms 48 and a link 51 adjacent to the 60 valves 47c and 47d, the link being actuated by contact with a pair of cams 52 oppositely positioned on the shaft 13 but in a longitudinal plane coincident with the axis of the shaft and perpendicular to the longitudinal axial plane in 70 which the cams 52, shown in Fig. 7, are positioned. The device actuating the valves 47c and 47d is similar in all respects to that shown in Figs. 6 and 7 for actuating the valves 47a and 47b and illustration thereof is omitted as be- 75

ing unnecessary to a proper understanding of the invention.

The two sets of cams 52 are so positioned on the shaft that the by-pass valves 41a and 41b are opened to admit the compressed air into the combustion chambers 11a and 11b as the pistons 26 on the rotor 14 are moving over the ends of the conduits 46a and 46b and remain open until the pistons, shown in dotted lines, clear the conduits, and have reached the position shown in Fig. 3. This position preferably corresponds to a travel of approximately ten degrees within the combustion chambers 11a and 11b, whereupon the valves 41a and 41b are instantaneously closed by the return movement of the link 51. The closure of the conduits 46a and 46b occurs on the instant that the corresponding pistons 29 have completed their compression stroke, and as a result, the air from the compression chambers 30a and 30b is driven into the combustion chambers 11a and 11b back of the pistons 26 at maximum pressure. Similarly, the compressed air in the compression chambers 30c and 30d is respectively admitted into the combustion chambers 12a and 12b through the conduits 46c and 46d at maximum pressure upon completion of the compression strokes of the adjacent pistons 29 positioned in said chambers.

A supply of fluid fuel is maintained in each by-pass valve 41a, 41b, 41c, and 41d the fuel being delivered preferably at a pressure of approximately 20 pounds by the operation of a pump, not shown. The fuel is delivered by the pump through ducts 61 provided by the casing 10 and apertures 61a formed in the side wall of the valves in registry with the ducts. As best illustrated in Figs. 4 and 5, the by-pass valves each provide a longitudinal bore or chamber 62, open at its upper end, and in which is positioned a reciprocally movable plunger rod 63 serving both as an injector and as a throttle for the fuel. A longitudinal bore or recess in the lower end of each rod 63 provides a chamber 64 extending to the periphery of the rod on one side to provide a narrow longitudinally extending slot or by-pass which is in register with the adjacent aperture 61a when the by-pass valve in which the rod is positioned is closed to the passage of air into the combustion chamber.

The lower end of each rod 63 is shown as spaced from the bottom of the bore 62 in approximately half throttling position and is movable longitudinally in the bore in a manner hereinafter more particularly described, to inject fuel into the adjacent combustion chamber. A duct 67, extending diagonally downward from the lower end of each bore 62 to the outer periphery of the by-pass valve, terminates adjacent the discharge end of the transverse bore 60. The discharge ends of the air conduits 46a, 46b, 46c and 46d each provide a recess 88 as shown in Fig. 5. Rotation of the by-pass valve through 90° to bring the bores 60 into register with the air conduits also registers the lower ends of the ducts 67 with the recesses 88, and permits the fuel to be discharged from the ducts and disseminated in highly atomized condition throughout the air flowing into the combustion chambers. The by-pass valves 41a and 41b are rotatable independently of the rods 63 positioned therein, and when the valves are in open position, the fuel ducts 61 are closed to admission of fuel by the outer periphery of the valves 46a and 46b. The upper ends of the chambers 64 are also closed when the valves are in open or air and

fuel discharging position, thereby preventing any backflow of fuel when injection takes place. Upon return of the by-pass valves to closed position, the discharge ends of the ducts 61 are uncovered and permit fuel to be pumped into the chambers 64 to replace that injected into the combustion chambers.

The rods 63 are moved inwardly to force fuel from the lower ends of the bores 62 through the ducts 67 by means of a tappet 68 carrying a roller 69 which rides over a pair of cams 70 formed on the shaft 13. The cams 70 are positioned on diametrically opposite sides of the rotor and approximately intermediate the longitudinal axial plane in which the cams 52 are positioned. A compression spring 71 holds the inner ends of a pair of rocker members 72 against the outer end of the tappet 68 and yields to permit upward movement of the tappet and corresponding rotation of the rocker members. The rocker members 72 are journalled at one end in brackets 13 and at the other end in the casing 10 as best shown in Figs. 1, 6, and 8.

The upper end of the rod 63, positioned in the by-pass valve 41a, is integrally formed with a transversely extending bar 74 and the upper end of the rod 63, positioned in the by-pass valve 41b, is integrally formed with a similar bar 75. The bars 74 and 75 have a close fitting tongue and groove connection, as shown in Fig. 4, 30 whereby the bars and the rods 63 connected therewith are moved together vertically by the rocking of the members 72. The members 72 are respectively operatively connected with the bars 74 and 75 by pins 77, projecting through elongated slots 78 provided in upwardly projecting flanges 79 formed on the bars. The pins 77 are each carried by a rack 80, respectively longitudinally movable in the members 72 in a manner and for a purpose hereinafter described. Rocking of the members 72 by the tappet 68 as above described oscillates the pins 77 in an arcuate path. The engagement of the oscillating pins 77 with the bars 74 and 75 results in corresponding vertical movement of the bars and the rods 63. Upward movement of the tappet 68 is so timed as to rock the members 72 to force the rods 63 downwardly at the instant the by-pass valves 41a and 41b are moved to open the conduits 46a and 46b to the delivery of charges of air and fuel into the combustion chambers 11a and 11b, respectively. Return of the tappet 68 downwardly to its original position, by the action of the spring 71 when the roller 69 has passed over a cam 70, moves the bars 74 and 75 and the rods 63 back to their respective positions shown in Figs. 4 and 5 wherein the valves 41a and 41b are closed. Since the tappet 68 is moved upwardly twice for each revolution of the rotor 14, two charges of air and fuel are delivered into the combustion chambers 11a and 11b during each revolution of the rotor. The injection devices for delivering fuel into the combustion chambers 12a and 12b, provided by the rotor 15, are identical in construction with the devices described for delivery of fuel and air into the chambers 11a and 11b and their operation is similar, other than that the delivery into the latter chambers occurs at timed intervals exactly intermediate the delivery into the former.

The bars 74 and 75 and the rods 63 are shown in Figs. 4 and 7 as at the end of their upward strokes resulting from rocking of the members 72. The quantity of fuel delivered into the combustion chambers with each air delivery obvi-

ously depends upon the length of the strokes of the rods 63 in the bores 62 of the by-pass valves. The length of such strokes and the position of the bars 74 and 75 and the rods 63 when the upward strokes are completed depend upon the position of the pins 77 in the inclined portions of the slots 78. The length of the arcs through which the pins 77 are oscillated depends upon the radial distance of the pins from the axes of oscillation of the members 72, since the racks 80 carrying the pins are rocked with the members. For any given position of the pins 77 in the inclined portion of the slots 78 there is a corresponding length of stroke of the rods 63 and a uniform injection of fuel through the ducts 67 by each stroke.

The position of the pins 77 in the slots 78 is shifted as hereinafter described to throttle the fuel. If the amount of fuel delivered by each stroke of the rods 63 is to be increased, this is accomplished by moving the pins 77 outwardly since the radial distance of the pins from the axes of rotation of the members 72 and the length of the arc through which the pins are oscillated are thereby increased. If the amount of fuel delivered with each charge is to be diminished, this is accomplished by movement of the pins 77 inwardly in the inclined portions of the slots 78, since the radius and the length of the arc of oscillation of the pins are thereby shortened. The described outward and inward movements of the pins 77, to accomplish throttling of the fuel, are along lines perpendicular to the axes of the rods 63, and since the slots are inclined as shown, the outward movement of the pins raises the bars 74 and 75, and the rods 63 respectively carried thereby. Inward movement of the pins 77 in the inclined portion of the slots 78 moves the bars 74 and 75 and the rods 63 downwardly so that the lower ends of the rods are closer to the bottom of the bores 62 in the by-pass valves. The position of the rods 63 in the by-pass valves for any setting of the pins 77 is such that the longitudinal stroke of the rods is accomplished without striking the bottom of the bores 62 in the by-pass valve.

The upper ends of the slots 78 terminate in arcuate portions having as their respective centers the axes of rotation of the rocker members 72, and when the pins 77 are positioned in the arcuate portions, their oscillation by the rocker members does not produce any vertical movement of the bars 74 and 75 and the rods 63 carried thereby, the rods remaining stationary in their most advanced position and as a result no fuel is delivered into the combustion chambers with the air.

The described shifting of the position of the pins 77 in the slots 78 to throttle the fuel by varying the length of strokes and the position of the rods 63 in the by-pass valves, is accomplished by outward and inward movement of the racks 80 carrying the pins. The racks 80 are respectively actuated by pinions 81 machined on shafts 82 journalled in the rocker members 72. The pinions 81 are positioned in bores 83 of generally cylindrical shape and providing openings through which the pinions project adjacent the racks 80 with such projecting portions in mesh with the racks.

The projecting ends of the two shafts 82 provide pinions 84 respectively in meshing engagement with one of a pair of vertically movable racks 85. The racks 85 are rigidly connected with one end of a bar 86 as best shown in Figs.

1 and 8. A throttling device, operable to control the movement of the rods 63 in the by-pass valves 47c and 47d, similar in construction and operation to the throttling device described for the rods 63 in valves 47a and 47b, has a pair of racks 85 rigidly connected to the other end of the bar 86. The bar 86 is movable vertically, by a longitudinally movable manually actuated throttle rod 87, to simultaneously actuate both pairs of racks 85. The rod 87 projects through the top of the casting 10 and downward movement thereof simultaneously actuates the racks 85 to rotate the shafts 82 to move the racks 80, and the pins 77 outwardly in the slots 78 in equal amounts. As a result of this outward movement, the length of the strokes of all the rods 63 are similarly and equally increased and the delivery of fuel to each combustion chamber is equally and evenly throttled. Upward movement of the throttling rod 87 likewise simultaneously moves the racks 85 to actuate the racks 80 and move the pins 77 inwardly in the slots 78 whereby the length of the strokes of all the rods 63 is decreased, and the amount of fuel injected into the combustion chambers is correspondingly diminished, such injection ceasing entirely when the pins 77 are in the arcuate portions of the slots 78.

From the foregoing description, it is obvious that all four of the pins 77 are moved to occupy similar positions in the slots 78 by manipulation of the rod 87. The full line intermediate position of the pins 77, shown in Fig. 4, corresponds to partial throttling of the injection devices and Fig. 5 illustrates the retracted position of the plunger rod 63 in the valve 47a corresponding to the illustrated full line position of the pin, it being understood that Fig. 5 also illustrates the fully retracted position of the rods 63 positioned in the valves 47b, 47c, and 47d respectively for the full line position of the pins in Fig. 4. In the illustrated full line position of the pins 77 in the slots 78 their oscillation by the rocker members 72 lowers the rods 63 from the position shown as hitherto described and then returns the rods to the position shown in Fig. 5. Obviously, the amount of fuel delivered through the ducts 67 by the downward movement of the rods 63 depends upon the length of their strokes and since this varies with the position of the pins 77, a maximum amount of fuel is delivered when the pins 77 are in the dotted line positions near the outer end of the slots and no fuel is delivered when the pins are in the dotted line position at the upper end of the slots, since in the latter position, the rods 63 are stationary with their inner ends in close proximity to the bottom walls of the bores or chambers 62 in the valves. Any position of the pins 77 intermediate the dotted line positions will correspondingly shift the position of the rods 63 in the bores or chambers 62 and will also vary the length of the strokes of the rods and the amount of fuel delivered by their reciprocation.

Thus, it will be seen that I have provided efficient and novel throttling and injection devices which are simple, durable, and satisfactory for their intended purpose.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A fuel injector pump of the kind described comprising a casing providing a bore, said casing also providing a fuel inlet conduit and a fuel discharge conduit each communicating with said bore, a barrel closely fitting said bore and having its inner end closed, means for imparting angular oscillation to said barrel, a plunger rod fitting snugly within said barrel, means for reciprocating the rod longitudinally within the barrel whereby the space between the inner end of the rod and the inner end of the barrel provides a pump chamber, the side wall of the barrel providing a port which communicates with said fuel inlet conduit when the barrel is at one end of its oscillatory path, the closed end of said barrel providing a relief duct connected with said chamber and which connects with said fuel discharge conduit when the barrel is at the other end of its oscillatory path, said rod extending inwardly beyond said barrel port and providing a recess or bore extending outwardly beyond said fuel inlet duct when the rod is at the beginning of its pump stroke, said recess terminating in a longitudinally elongated laterally extending orifice positioned to receive fuel from the inlet conduit when said barrel port is in communication with said conduit, said barrel and plunger rod being operable in timed relation whereby the rod, in approaching the end of its return stroke moves the orifice to open said port while it is in communication with the fuel inlet conduit and the rod during its initial pump stroke covers said port simultaneously with movement of the barrel to a position wherein the relief duct communicates with said fuel discharge conduit, said barrel being moved to close the relief duct upon completion of the pump stroke of said rod.
2. A fuel injector pump of the kind described comprising a casing providing a bore, said casing also providing a fuel inlet conduit and a fuel outlet conduit each communicating with said bore, a barrel closely fitting said bore and having its inner end closed, means for imparting angular oscillation to said barrel, a plunger rod fitting snugly within said barrel, means for reciprocating the rod longitudinally within the barrel whereby the space between the inner ends of the rod and the barrel provides a pump chamber, the side wall of the barrel providing a port which communicates with said fuel inlet conduit when the barrel is at one end of its oscillatory path, the closed end of said barrel providing a relief duct connected with said chamber and which connects with said fuel outlet conduit when the barrel is at the other end of its oscillatory path, said barrel and rod being operable in timed relation whereby the rod, in approaching the end of its return stroke, uncovers said port while it is in communication with the fuel inlet conduit and the rod, during its initial pump stroke, covers said port simultaneously with the movement of the barrel to a position wherein the relief duct communicates with said fuel outlet conduit, said barrel being moved to close the relief duct upon completion of the pump stroke of said rod, and means operable to control said rod reciprocating means to vary the length of strokes of the rod and thereby to regulate the amount of fuel delivered through said relief duct into the outlet conduit by each pump stroke of the rod.
3. A fuel injector pump of the kind described comprising a casing providing a bore, said casing also providing a fuel inlet conduit and a fuel discharge conduit each communicating with said bore, a barrel closely fitting said bore and having its inner end closed, means for imparting angular oscillation to said barrel, a plunger rod fitting snugly within said barrel, means for reciprocating the plunger rod longitudinally within the barrel whereby the space between the inner ends of the rod and the barrel provides a pump chamber, the side wall of the barrel providing a port which communicates with said fuel inlet conduit when the barrel is at one end of its oscillatory path, the closed end of said barrel providing a relief duct connected with said chamber and which connects with said fuel discharge conduit when the barrel is at the other end of its oscillatory path, said rod extending inwardly beyond said barrel port and providing a recess or bore extending outwardly beyond said fuel inlet duct when the rod is at the beginning of its pump stroke, said recess terminating in a longitudinally elongated laterally extending orifice positioned to receive fuel from the inlet conduit when said port is in communication with said conduit, said barrel and plunger rod being operable in timed relation whereby the rod, in approaching the end of its return stroke moves the orifice to open said port while it is in communication with the fuel inlet conduit and the rod during its initial pump stroke covers said port simultaneously with movement of the barrel to a position wherein the relief duct communicates with said fuel discharge conduit, said barrel being moved to close the relief duct upon completion of the pump stroke of said rod, and means operable to control said rod reciprocating means to vary the length of the rod stroke and thereby to regulate the amount of fuel delivered through said relief duct by each pump stroke of said rod.

MICHAEL E. BAFARO.
